UNITED STATES PATENT OFFICE.

ERNEST H. EULER, OF BLAIR, KANSAS.

HAIR-PIN.

1,070,438.

Specification of Letters Patent. Patented Aug. 19, 1913.

Application filed October 6, 1910. Serial No. 585,658.

To all whom it may concern:

Be it known that I, ERNEST H. EULER, a citizen of the United States, residing at Blair, in the county of Doniphan and State 5 of Kansas, have invented new and useful Improvements in Hair-Pins, of which the following is a specification.

This invention relates to hair pins and the object of the invention is to provide a 10 simple, efficient and durable hair fastening device which will not become loosened and which at all times will hold the hair in proper position, until it is desired to remove the same.

15 Further objects of the invention will appear as the following specific description is read in connection with the accompanying drawing which forms a part of this application, and in which:

20 Figure 1 is a side elevation showing the device in locked position. Fig. 2 is a longitudinal section therethrough showing the locking yoke in raised position.

Referring more particularly to the drawing 25 1 represents a tubular member which has a portion of one of its sides cut away to form an open slot 2. The tubular member is bent into U-shape between the ends of the slot and is provided on its inner side with apertures 3 and 4 which are arranged opposite 30 each other for a purpose to be hereinafter described.

A yoke-shaped operating rod 5 has its ends or opposite legs 6 and 7 inserted in the 35 tubular portion and carries the pivoted locking dogs or fingers 8. The locking dog on one of the legs for instance is pivoted to the forward side of the leg while the locking dog upon the opposite leg is pivoted to the 40 rear side of said leg so that when thrown into operative position through the apertures 3 and 4 as will hereinafter be described, the locking dogs or fingers will overlap each 45 other and hold the hair which is between the legs of the U-shaped member 1 from disengagement therewith.

Inserted into the ends of the tubular member 1 are pointed plugs 9 which have their inner ends beveled as at 10 to engage the beveled outer faces 11 of the dogs 8 and 50 force them through the apertures 3 and 4 when the yoke-shaped operating rod 5 is forced downwardly.

In the operation of the device, the U-shaped member is inserted in the hair with 55 the yoke member retracted so that the locking dogs are not exposed through the apertures, and when the member is in proper position, the yoke-shaped member is forced 60 inwardly so that the beveled outer faces of the locking dogs contact with the beveled inner ends of the plugs and force the dogs outwardly past each other.

Having thus described the invention, what 65 is claimed is—

A hair pin comprising a tubular U-shaped member having oppositely arranged apertures in the inner sides of the legs thereof, a U-shaped operating member slidably mounted in the tubular member, a locking dog pivoted at the lower end of each leg of the said operating member, entering points secured in and closing the ends of the U-shaped member and having their inner ends beveled to form cam surfaces, the said 75 locking dogs being adapted to engage the said cam surfaces and to project inwardly toward each other through the said apertures, said locking dogs being arranged out of alinement so that when in locking position the points thereof will pass each other and overlap to provide a locking bar extended transversely between the said U-shaped tubular members.

In testimony whereof I affix my signature 85 in presence of two witnesses.

ERNEST H. EULER.

Witnesses:

A. L. HULL,
H. S. ESTES.
